UNITED STATES PATENT OFFICE.

WILLIAM S. THOWBRIDGE, OF CHICAGO, ILLINOIS, ASSIGNOR TO AMERICAN STEEL
FOUNDRIES, OF CHICAGO, ILLINOIS, A CORPORATION OF NEW JERSEY.

TRUCK-SIDE-FRAME ARRANGEMENT.

1,890,811.

Specification of Letters Patent. Patented Sept. 13, 1921.

Application filed April 8, 1920. Serial No. 372,323.

To all whom it may concern:

Be it known that I, WILLIAM S. THOWBRIDGE, a citizen of the United States, residing at Chicago, in the county of Cook and State of Illinois, have invented certain new and useful Improvements in Truck-Side-Frame Arrangements, of which the following is a specification.

This invention relates to a cast side frame. 10 In an application, Serial No. 344,769, filed December 15, 1919, George G. Floyd sets forth causes and effects of compression, tension and bending stresses set up in a cast metal side frame and which are peculiar to 15 the cast type of side frame.

My present invention is of the same general character as that disclosed in said Floyd application. More strictly speaking, it is a modification thereof. So far as the compression, tension and bending stresses set up in a 20 cast metal side frame are concerned, the problem is the same. My specific arrangement for overcoming such stresses is different. In view of the fact that the subject is 25 so thoroughly considered in said Floyd application no repetition will be made in this application on the subject-matter claimed in the Floyd application, and only such points as are necessary to a complete understanding 30 of this invention will be considered.

One object of this invention is to provide a cast metal truck side frame in which the tension and bending stresses are reduced in a manner to meet the various requirements 35 of service conditions.

Another object is to connect journal boxes to truck side frames in a simple and efficient manner.

These and other objects are accomplished 40 by means of the arrangement disclosed on the accompanying sheet of drawings, in which—

Figure 1 is a fragmentary side elevation, parts being in section, of a truck side frame embodying my invention;

45 Fig. 2 is a top plan view of the same;

Fig. 3 is a sectional view taken in the planes of irregular lines 3—3 of Fig. 1;

Fig. 4 is a detail sectional view taken in the plane of line 4—4 of Fig. 1; and,

50 Fig. 5 is a detail plan view of the connection of the journal box tie bar to the side frame.

The various novel features of the invention will be apparent from the following

description and drawings and will be particularly pointed out in the appended claims.

Referring to the figures of the drawings, it will be noted that I have shown a truck side frame having a tension member 10, compression member 11, columns 12 and journal box 20 receiving portions 13, all cast in a single piece. It is an established fact, as clearly brought out in said Floyd application, that the highest tension and bending stresses in cast metal truck side frames used heretofore 65 occur at points 14, 15 and 16. These high tension and bending stresses are overcome in this particular arrangement by providing the tension member with a web 17 which, between the columns and under the columns 70 12, is located at the upper side of the tension member, said web portion extending diagonally downwardly with respect to the side walls 18 and 19 of the tension member to the point 16, where it reaches the lower side 75 of the tension member and from said point forms a gradual curve throughout the remaining length outwardly of the truck side frame over the journal box 20. The web 21 of the compression member between and over 80 the columns 12 is at the upper side of the compression member and from the columns, extends diagonally downwardly with respect to the sides 22 and 23 of the compression member to a point 24, where said web member 21 meets the web member 16 of the tension member, from which point said webs continue unitedly over the journal box, as hereinabove set forth. In other words, the webs 17 and 21 of the tension and compression members 10 and 11, respectively, converge toward each other from the columns 12 substantially in straight lines and join each other at the point 24 over the journal box. The side walls 18 and 19 of the tension member 10 and the side walls 22 and 23 of the compression member 11 extend both above and below the webs 17 and 21, respectively, the amount differing along the length of 90 95 said members.

100 This design is worked out primarily for use with the standard Master Car Builders' journal box, such as is shown herein. It is found, as a matter of design, including strength and durability, that it would not be 105 advisable to make a short turn at the point 16, and in order to establish an easy and efficient curve at the upper end of the ten-

sion member, and more particularly in the web thereof, I propose to use a filler block 25 on the top of the journal box 20 and between the latter and the under side of the side frame, the lower edge 26 of the filler block being straight to fit the top of the journal box 20, and the upper surface or flange 27 of the filler block having an easy radius or curve which will give an easy curve at this point for the stresses to follow. Accordingly, the curve in the upper end of the web 17 of the tension member is curved in a manner such that the stresses can easily follow same without causing undue strain to the parts in question. This filler block 25 at its upper side is provided with gibs 28 and 29 which embrace the side walls of the side frame at the ends thereof. One end of the filler block is provided with an opening 30 which registers vertically with an opening 31 in the side frame through which a journal box bolt 32 passes, said bolt also passing through openings in the journal box lugs 33 and 34. The other end of the 25 filler block is provided with a round pin or projection 35 which extends downwardly into the opening 36 of the journal box lug 37. The opening 38 in the associated journal box lug 39 receives a similar projection 40 which is mounted upon a journal box tie bar 41, through the outer end of which the bolt 32 extends. The tie bar is secured to the outer end of the journal box by a nut 42 which coöperates with the lower end of the bolt 32. The other end of the tie bar extends through an opening 43 in the web 17 of the tension member and has at its end a threaded portion 44 which coöperates with a nut 45 by means of which the tie bar is 40 secured to the side frame. A nut lock 46 is provided, one flange of which engages a boss 47 formed on the web 17, and the other flange of the nut lock engages a side on the nut. By means of the projections 35 and 40 45 on the filler block 25 and tie bar 41, respectively, the inner bolt lug may be disposed of entirely. By means of the gibs 28 and 29 embracing the sides of the side frame, and by means of the bolt 32, filler block projection 35, tie bar projection 40, and the tie bar being anchored to the web 17 of the tension member, the journal box is securely held in operative position without puncturing the two main webs of the side frame near 50 their point of juncture for the reception of an inner journal box bolt.

It is my intention to cover all modifications of the invention falling within the spirit and scope of the following claims.

60 I claim:

1. A truck side frame including integrally-formed tension and compression members having webs which extend diagonally with respect to the length of said 65 respective tension and compression members

and are joined to each other at the journal box receiving portion.

2. A truck side frame including integrally-formed tension and compression members having webs which extend lengthwise of the respective members and diagonally with respect thereto and are joined to each other at the lower side of the journal box receiving portion. 70

3. A truck side frame including integrally-formed tension and compression members having webs which extend diagonally with respect to the length of said respective tension and compression members, the web of the tension member being curved near its outer end and joined with the web of the compression member at the journal box receiving portion. 75

4. In combination, a truck side frame including integrally-formed tension and compression members having webs which extend diagonally with respect to the length of said respective tension and compression members, the web of the tension member being curved near its outer end and joined with the web of the compression member at the journal box receiving portion, a journal box, and a filler block, the lower surface of which conforms with the upper surface of the journal box, and the upper surface of which filler block conforms with the lower surface of the journal box receiving portion of the side frame. 80

5. In combination, a truck side frame having a curved journal box receiving portion, 100 a journal box, the upper surface of which is flat, and a filler block interposed between the journal box and journal box receiving portion of the side frame, the coöperating surfaces of the journal box, side frame 105 and filler block coöperatively conforming.

6. In combination, a truck side frame having a journal box receiving portion, a journal box, and a filler block interposed between said journal box and journal box receiving portion of the side frame, said filler block and journal box having interlocking 110 means coöperating to hold the journal box in place.

7. In combination, a truck side frame 115 having a journal box receiving portion, a journal box, and a filler block interposed between said journal box and journal box receiving portion of the side frame, said filler block and journal box having interlocking 120 means coöperating to hold the journal box in place, and said side frame and filler block also having interlocking means.

8. In combination, a truck side frame having a journal box receiving portion, a journal box, and a filler block interposed between said journal box and journal box receiving portion of the side frame, said filler block and journal box having interlocking 125 means coöperating to hold the journal box 130

in place, and a journal box tie bar having interlocking means with the journal box for coöperating to hold the latter in position.

9. In combination, a truck side frame 5 having a journal box receiving portion, a journal box, and a filler block interposed between said journal box and journal box receiving portion of the side frame, said filler block and journal box having interlocking 10 means coöperating to hold the journal box in place, said side frame and filler block having interlocking portions, and a journal box tie bar having interlocking means with the journal box for coöperating to hold the 15 latter in position.
10. In combination, a truck side frame, a journal box having bolt openings, a filler block interposed between said side frame and journal box having a projection extending 20 into one of said bolt openings, and a tie bar having a projection extending into another one of said bolt openings and secured to the side frame for securing the journal box in position.
11. In combination, a truck side frame, 25 a journal box, a filler block interposed between the side frame and journal box having a projection extending into an opening of said journal box, a tie bar having a projection extending into another opening of said journal box and being secured to the tension member of the side frame for securing the journal box in position, and a bolt extending through a portion of the side frame, 30 filler block, journal box and tie bar for assisting in holding the journal box in position.

Signed at Chicago, Illinois, this 24th day of March, 1920.

WILLIAM S. TROWBRIDGE.
